5 Claims. (Cl. 260—666)

The present invention relates to a process for the production of 1-methylcyclohexene-(1), represented by the structural formula, viz.

from 1-methylcyclohexene-(3) represented by the structural formula, viz.

or 1-methylcyclohexene-(2) represented by the structural formula, viz.

in liquid ammonia by use of a substance selected from the group consisting of alkali metals, alkaline earth metals, alkali metal amides and alkaline earth metal amides.

The essential object of this invention is to provide a process for producing easily and completely 1-methylcyclohexene-(1) from 1-methylcyclohexene-(2) or 1-methylcyclohexene-(3) by an isomerization reaction wherein a peculiarity of liquid ammonia is utilized.

The present inventors have studied the organic chemistry field employing liquid ammonia and its application. The present invention is based on a part of their studies.

As the result of said studies, the present inventors have found that 1-methylcyclohexene-(2)

or 1-methylcyclohexene-(3)

is isomerized into 1-methylcyclohexene-(1)

which is considered to have the most stable structure, in liquid ammonia in the presence of a substance selected from the group consisting of alkali metals, alkaline earth metals, and the amides thereof.

Since the alkali metals, alkaline earth metals, or their

2

amides employed in the above-mentioned case act as catalysts, their quantity so employed has no relation to the quantity of 1-methylcyclohexene-(3)

or 1-methylcyclohexene-(2)

As the alkali metals, Li, Na, and K may be used; and as the alkaline earth metals, Ca, Sr, and Ba may be used. All of the amides of the abovementioned metals may be employed as amides. However, sodium amide and potassium amide are excellent in view of their practicality and solubility.

The reaction temperature is not limited.

Example I

25 20 cc. of liquid ammonia, 2 g. of 1-methylcyclohexene-(3)

and 0.1 g. of metallic sodium were placed in a pressure-resistant glass reaction tube having a capacity of 50 cc., and left standing at 20° C. for 8 hours. Thereafter, 35 ammonia was recovered and 20 cc. of water was gradually added to the residue. As the result of an analysis of the oil layer by gas chromatography, it was found that the said 1-methylcyclohexene-(3)

45 was isomerized into 1-methylcyclohexene-(1)

at 100%.

Example II

55 20 cc. of liquid ammonia, 2 g. of 1-methylcyclohexene-(2)

60 and 0.2 g. of potassiumamide were placed in a pressure-resistant glass reaction tube having a capacity of 50 cc., and left standing at 40° C. for 3 hours. Then, the same 65 procedure as that in Example (I) was carried out, whereby said 1-methylcyclohexene-(2)

was isomerized into 1-methylcyclohexene-(1)

at 100%.

As described above, according to the present invention since 1-methylcyclohexene-(1)

can be easily and completely produced from 1-methylcyclohexene-(2)

or 1-methylcyclohexene-(3)

by an isomerization reaction by utilizing a peculiarity of 30 liquid ammonia, the present invention effectively contributes to the progress of petroleum chemical industry utilizing 1-methylcyclohexene-(1)

Accordingly, it will be observed that the present invention is very useful in the petroleum chemical industry.

What is claimed is:

1. A process for production of 1-methylcyclohexene-5 (1) consisting essentially of: contacting in liquid ammonia a compound selected from the group consisting of 1-methylcyclohexene-(2) and 1-methylcyclohexene-(3) with a substance selected from the group consisting of alkali metals, alkaline earth metals, alkali metal amides and alkaline earth metal amides, whereby an isomerization reaction takes place to produce 1-methylcyclohexene-(1).

10 2. A process according to claim 1, wherein said alkali metal is selected from group consisting of lithium, sodium and potassium.

15 3. A process according to claim 1, wherein said alkaline earth metal is selected from group consisting of calcium, strontium and barium.

20 4. A process according to claim 1, wherein said alkali metal amide is selected from group consisting of lithium amide, sodium amide and potassium amide.

25 5. A process according to claim 1, wherein said alkaline earth metal amide is selected from group consisting of calcium amide, strontium amide and barium amide.
